UNITED STATES PATENT OFFICE.

FRANK P. HEMMING AND CARL HENRY HEMMING, OF NEW HAVEN, CONNECTICUT.

CUTLERY-GRINDING MACHINE.

Application filed September 27, 1921. Serial No. 503,578.

To all whom it may concern:

Be it known that we, FRANK P. HEMMING and CARL H. HEMMING, citizens of the United States, residing at New Haven, in 5 the county of New Haven and State of Connecticut, have invented certain new and useful Improvements in Cutlery-Grinding Machines; and we do hereby declare the following to be a full, clear, and exact description 10 of the invention, such as will enable others skilled in the art to which it appertains, to make and use the same.

This invention relates to certain improvements in cutlery grinding machines. In 15 carrying out the invention, certain well known elements relating to machines of this character are employed, such, for instance, as an emery wheel, preferably of the hollow or cup shaped type, rotatably 20 mounted in close proximity to the blade to be ground, said blade being mounted on a holder attached to a reciprocating member having a quick idle movement in one direction, and a slow return movement for grinding; also the employment of well known 25 planet gear mechanism to effect the slow and rapid movement of the reciprocating member.

One of the objects of the present invention is to provide means whereby the shoulder of a knife blade is positively located with respect to the corner of the grinding wheel at the termination of the idle travel of the reciprocating member carrying 35 the knife blade holder.

The reciprocating member consists of a plate slidably mounted on a pivotally supported carriage, said carriage adapted to have a movement to and from the grinding 40 wheel. A coarse pitch screw is journaled in the carriage carrying a nut adapted to engage with adjustable mechanism on the underside of the sliding plate to reciprocate said plate. At the termination of the quick 45 idle travel of the sliding plate it is imperative that it be brought firmly against a stop in order to positively locate the shoulder of the knife blade with respect to the grinding wheel. For this purpose, the nut is allowed 50 an idle travel beyond the predetermined idle travel of the slide, and a reverse idle travel while the carriage is being moved toward the grinding wheel.

Another improved feature consists in as- 55 sembling the planet gear mechanism within

a pulley, and mounting the pulley on the shaft of the slide actuating screw to serve both as a driving pulley and a balance wheel to maintain a steady and continuous rotation of the screw. 60

Referring to the accompanying drawings wherein the same reference characters indicate like parts throughout the several views:

Figure 1 represents a plan view of the machine showing the carriage in its outer position with respect to the grinding wheel, and the sliding plate located at the termination of the idle travel, also sectional view of the handle lever; 65

Figure 2 is a side elevation of the machine looking in the direction of arrow *a*, Figure 1;

Figure 3 is a view of the machine looking in the direction of arrow *b*, Figure 1; 70

Figure 4 is a plan view of the carriage with the sliding plate removed, also sectional view of the driving and loose pulleys mounted on the screw shaft, and sectional view of the handle lever; 75

Figure 5 is a detail elevation of the driving pulley and planet gear mechanism with the loose pulley removed;

Figure 6 is a broken view of the neck of the carriage and screw shaft, and sectional view of the driving pulley with the loose pulley removed, showing the planet gear mechanism in position for a slow return movement of the sliding plate to grind; 85

Figure 7 is a detail inside view of the sliding plate; 90

Figure 8 is a sectional view of the sliding plate on line 8, 8, of Figure 7, and broken view of the sliding plate actuating screw, and

Figure 9 is a broken view of the slide actuating nut, part of the slide mechanism, full view of the follower and its support showing the roller carried by the nut forced to one side to permit the return of the carriage. 100

The principal common features incidental to machines of this character comprise the bed 1, slide 2, adjusting screw 3 therefor, slide standards 4 in which is journaled the shaft 5 carrying the emery grinding wheel 6, and the tight and loose pulleys 7 and 7^a. 105

8 is a plate adapted to be set at any angle with respect to the grinding wheel and is secured in any of its adjusted positions by 110

means of the bolts 9 projecting from the bed 1.

The carriage 10 is provided with the foot 11 pivotally supported at one corner on the 5 stud 12, Figure 3, of the base plate 8 and it projects through the hub 13, Figures 1 and 4, of the carriage foot 11.

The shaft ends 14, 15, of the screw 16 are journaled, Figure 4, in the ends of the 10 carriage. The latter shaft carrying the driving pulley 17 with its internal planet gear mechanism and adjacent clutch mechanism, presently to be more fully described. 17^a is a loose pulley adjacent to pulley 17. 15 18 is a nut operatively mounted on the screw 16 having the lug 19 adapted to effect a longitudinal reciprocating movement of the sliding plate 20, mounted on the carriage, by its contact with the adjustable rod 20 21, Figures 7 and 8, mounted in the bracket 22, and the rod 23 of the bracket 24 located in alignment with the rod 21. 25 is a spring on rod 23 adapted to be compressed through the medium of the sleeve 26 when the lug 25 19 contacts with the end of the rod, as shown in Figure 8. The position of rod 23 and sleeve 26 are adjusted by means of the jam nuts 27, 28 mounted on the ends of said rod. 29 is the knife blade holder which 30 may be of any desired construction best adapted to support the blade to be ground.

30 is a bracket projecting from the nut 18, carrying the lever 31 pivoted thereto, and is normally held against the pin 32, 35 Figure 4, of the bracket by the spring 33. 34 is a roll in the outer end of the lever adapted to travel along the face of the former 35 during the travel of the nut 18. The former being removably mounted in 40 the standard 36 attached, Figures 1, 2, and 3, to the stationary plate 8.

The pulley 17, Figures 4, 5, and 6, has the arm 37 journaled on the shaft end 15 of screw 16. The gear 38 is fast to the shaft, and the gear 39, with its clutch sleeve 40, is journaled on the shaft. 41 and 42 are short shafts anchored in the pulley arm and on which are journaled the pinions 43, 44, 45, and 46, meshing with gears 38 and 39. When the clutch pins 47 of the gear 39, and the clutch pins 48 of the pulley arm are engaged, Figure 4; and the clutch pins 49 of the clutch sleeve 40 are disengaged from the pin 50 of the carriage extension 51, the gears and pinions will be locked to the pulley and all rotate together for a fast rotation of the screw 16 to impart a rapid forward idle travel of the slide 20. When the clutch pins 49 are 60 locked to the stationary pin 50 of the carriage, and the clutch pins 47, 48, disengaged by the withdrawal of the gear 39 and sleeve 40, Figure 6; the gear 39 will remain stationary, and the rotation of the pulley 17 will carry the pinions 43, 44, 45, and 46,

around the gears 38 and 39. The pinions 43, 44, having one tooth more than the pinions 45, 46, the screw 16 will have a slow rotation to impart a slow return movement to the slide 20 during the grinding operation. When all of the clutch pins are disengaged, the pulley 17 will run idle.

52, Figures 1, 3, and 4, is a lever journaled on the stud 53 for actuating the clutch sleeve 40 through the medium of the 75 shipper rod 54 and handle lever 55. This rod is operatively supported in the standards 56, 57, of the carriage foot 11. As the lever 52 is located above the shipper rod 54, it is connected therewith through the 80 medium of the block 58 and the short rod 59.

The operation of the machine is as follows:—

At the termination of the forward idle 85 travel of the sliding plate 20, the lug 60, Figure 7, of the plate should be forcibly brought against the stop 61, Figure 4, of the carriage 10. This stop is intended to locate the position of the shoulder of a 90 knife blade with respect to the corner of the grinding wheel, so that the corner of the wheel will always engage said shoulder before the grinding operation of the rest of the blade begins.

95

There are, however, several causes operating to prevent the positive contact of the lug 60 with the stop 61, such, for instance, as the lost motion due to the wear of the mechanism for actuating the reciprocating 100 slide, or undue tightness or lack of lubrication of the slide will cause it to lag behind and fall short of the proper halting point.

To insure positive engagement of the slide 105 with the carriage stop, the nut 18 of the screw will continue its inward travel beyond the predetermined travel of the slide, and, in doing so, will compress the spring 25, Figure 8, through the medium of the 110 lug 19 of the nut, as before mentioned. During this spring compression, the trip 62, carried by the bracket 30 of the nut, Figure 4, will engage the adjustable stop 63 on rod 54 to reverse said rod and engage the clutch pins 49, 50, for a preliminary slow 115 idle reverse travel of the nut.

This idle reverse movement of the nut will bring the roll 34 first in contact with the incline 64 of the former 35. As the 120 roller is moved up this incline, it crowds the carriage 10 gradually toward the grinding wheel in the direction of arrow *c*, Figure 1, which gradual movement of the carriage is essential where a large amount of stock 125 has to be removed from a blade, as it enables the grinding wheel to gradually work its way to the proper depth into the stock of the blade without apparent injury to the sharp corner of the wheel, a result that 130

could not be obtained were the carriage suddenly thrown its ultimate distance at once.

As soon as the roll 34 has reached the straight face 35^a of the former, the idle travel of the nut will cease, and its lug 19 will contact with the rod 21 of the slide and carry said slide slowly back during the grinding operation, and when said grinding operation is completed, the trip 62 will contact with the adjustable stop 65 and halt the travel of the nut by the disengagement of the clutch pins 49, 50. Before this tripping is effected, the adjustable rod 66, Figure 9, of the carriage will contact with the roll carrying lever 31 and throw the roll out of vertical alignment with the bracket 30 so that the carriage may be returned against the adjustable stop screw 67 by the spring 68 located between the projection 69 of the stationary plate 8, and the projection 70 of the carriage foot 11, as shown more clearly in Figures 1 and 2.

As grinding wheels vary in texture, it is necessary that a soft or semispongy wheel remain in operation longer at the shoulder of the blade before the slide has started slowly back, than would be required of a wheel of harder texture. This idle travel of the nut is regulated in accordance with the texture of the grinding wheel by means of the adjusting rod 21 of the slide. In other words, the distance between the inner end of the rod 21 and the lug 19 of the nut is increased or decreased to give a longer or shorter idle travel to the nut before its lug 19 contacts with said rod to effect the reverse movement of the sliding plate 20.

The face 35^a of the former is shown as a straight surface, for the purpose of grinding the straight faces of cutlery blades, but it will be understood that any irregular shaped article can be ground on this machine by simply changing the contour of the former, to correspond to such irregular articles.

Having thus described our invention what we claim is:—

1. A cutlery grinding machine comprising a grinding wheel, a pivotally supported carriage, a knife holder carrying sliding plate adapted to have a reciprocating movement on the carriage, a rotatable screw journaled in the carriage, a nut operatively mounted on the screw, means on the plate adapted to be engaged by the nut to reciprocate the plate, one of said means being adjustable to enable the nut to have a predetermined idle travel on the screw and means to effect a lateral movement of the carriage toward the grinding wheel when the plate is at rest.

2. A cutlery grinding machine comprising a grinding wheel, a pivotally supported carriage, a sliding plate adapted to have a reciprocating movement on the carriage, means

to effect a lateral movement of the carriage toward the grinding wheel, a rotatable screw journaled in the carriage, a nut operatively mounted on the screw, means on the plate adapted to be engaged by the nut to reciprocate the plate, one of said means under spring tension to permit the nut to have an idle travel in one direction to insure the plate being brought against a positive stop, the other of said means being adjustable to permit the nut to have a predetermined idle travel in the opposite direction while the plate is at rest and during said lateral movement of the carriage.

3. A cutlery grinding machine comprising an abrasion wheel, a stationary support, a carriage pivotally mounted on the support and adapted to having a swinging movement to and from the abrasion wheel, a sliding plate mounted on the carriage, a knife holder on the plate, a screw journaled in the carriage, a traveling nut mounted on the screw, means on the plate adapted to be engaged by the nut to reciprocate the plate, a driving pulley mounted on the screw shaft, planet gear mechanism located within the pulley, said pulley and planet gear mechanism adapted to effect a rapid idle travel of the sliding plate in one direction, and a slow reverse travel in the opposite direction.

4. A cutlery grinding machine comprising a carriage, a plate mounted thereon, a knife holder on the plate, a rotatable screw journaled in the carriage, a nut having a reciprocating travel on the screw, means on the plate to be engaged by the nut to reciprocate the plate and also effect a predetermined idle travel of the nut in either direction when the plate is at rest.

5. A cutlery grinding machine comprising an abrasion wheel, a pivotally supported carriage, a sliding plate mounted on the carriage, a screw journaled in the carriage, means for rotating the screw, a nut mounted on the screw and having a reciprocating travel thereon, means on the plate to be engaged by the nut to reciprocate said plate and also effect an idle travel of the nut in either direction while the plate is halted, a former adjacent to the carriage having an incline face at one end thereof, means on the nut adapted to engage said incline and thus cause the carriage to be moved toward the abrasion wheel while the plate is halted, and means for returning the carriage at the conclusion of the grinding operation.

6. A cutlery grinding machine comprising an abrasion wheel, a pivotally supported carriage, a reciprocating plate mounted thereon, a knife holder on the plate, a rotatable screw journaled in the carriage, a reciprocating nut mounted on the screw, nut engaging means on the plate whereby said plate is reciprocated and halted to allow the nut to have an idle travel in either direc-

tion, a stationary former having an incline face, a roll carried by the nut under spring tension to engage said incline to move the carriage into contact with the abrasion wheel while the plate is halted, means for temporarily disengaging the roll from its operative engagement with the former, and means for

returning the carriage after the grinding operation.

In testimony whereof we affix our signatures.

FRANK P. HEMMING.
CARL HENRY HEMMING.
